UNITED STATES PATENT OFFICE.

GEORG KIRKEGAARD, OF NEW YORK, N. Y., ASSIGNOR TO IMPERIAL STOPPER COMPANY, A CORPORATION OF MAINE.

BOTTLE-STOPPER.

No. 890,141.

Specification of Letters Patent.

Patented June 9, 1908.

Application filed April 1, 1908. Serial No. 424,515.

To all whom it may concern:

Be it known that I, GEORG KIRKEGAARD, a citizen of the United States, residing at the city of New York, in the borough of Brooklyn and State of New York, have invented certain new and useful Improvements in Bottle-Stoppers, of which the following is a full, clear, and exact description.

This invention relates to bottle and jar stoppers or closures of that particular class comprising a metallic cap containing a packing disk and having means for securing it externally to the neck or mouth of the bottle, with the packing disk duly compressed to form a hermetic seal. Bottles which are usually sealed with this kind of a stopper are of comparatively thick and heavy glass to withstand the internal pressures, in consequence of which, the width or thickness of the glass at the lips of the bottle upon which the packing rests is considerable, and the packing disk which has heretofore been used has extended across the diameter of the mouth of the bottle and overlaid the entire thickness of the lips of the bottle. I have discovered that an effective seal can be obtained in this type of stopper with a packing disk of less diameter than those used heretofore, and by making use of this discovery, I am able to economize very considerably in the amount of cork or other packing material which is used, which becomes an item of considerable importance in the manufacture of large numbers of these stoppers. This economy in the manufacture is the principal object of the present invention, and the means for accomplishing it will now be described in detail.

In the accompanying drawing, Figure 1 is a side elevation of a form of stopper of my own invention, modified to receive the packing disk of reduced size and constituting the present invention; Fig. 2 is a plan of this stopper looking at the bottom or inside of the same. Fig. 3 is a section of the same stopper taken on line $x-x$ of Fig. 2, as applied to an ordinary commercial form of bottle; and Fig. 4 is a sectional view of another type of stopper showing my improved packing disk of reduced size applied thereto in a modified way.

It is to be understood that the improvements herein described in the packing disk are applicable to any of the types of stopper comprising the metal cap and having suitable

means to engage with the usual external annular shoulder on the bottle.

a represents the metal cap, and *b* a flange depending therefrom and suitably shaped with inwardly bent lips, as in Figs. 1, 2 and 3, 60 or with corrugations as in Fig. 4, or in any other conformation, which, when forced inward by the capping machine, will engage the shoulder *c* on the bottle.

e represents the improved packing disk, 65 ordinarily of cork, but which may be of any other material. This packing disk, instead of being of a diameter equal to the internal diameter of the cap, is substantially smaller than the diameter of the cap, but greater 70 than the bore of the neck of the bottle, so that instead of extending fully across the top or lips *d* of the bottle, it rests at its edge on top of the inner half or inner portion of the lips of the bottle. The disk is therefore 75 placed and secured concentrically in the metal cap, and leaves an annular space *f* around its edge which heretofore has been occupied by the larger disk, and which determines the amount of saving of cork or 80 other material which is effected by my invention.

In order to secure the disk in the cap, I annularly depress the outer corner of the cap as shown at *g*, so that the top of the cap will 85 reform a circular seat of the right size to receive the disk, and the disk is then secured in this seat either by cement or by bending inward tongues of the metal near the edge of the disk and forcing the points of said 90 tongues into or under the cork. These tongues are indicated by *i*, and may be given any other desired shape, and may, in fact, be substituted by embossings, which would have the same effect. 95

In Fig. 4, the metal cap is shown of the usual full size across the top, the disk being merely cemented in a concentric position to the flat inner surface of the cap.

When a cap equipped with this small disk 100 is applied to the bottle, the edge of the disk overreaches the inner portions or surfaces of the lips *d* of the bottle, as clearly shown in Fig. 3. The contacting surface between the disk and the bottle while being smaller in extent than in the stoppers heretofore used, is, nevertheless, sufficient to effectively seal the bottle, my discovery being that any larger surface of contact between the disk and bottle, such as heretofore used, is superfluous. 110

When the pressure is put upon the disk in the operation of sealing the bottle, the edges of the disk are more or less flattened and spread, so that the seal becomes entirely effective and will hold the highest internal pressures. It will be observed that when the bottle is sealed, the openings caused by the forming of the tongues *i* are outside of the sealing surface, so that no leakage is caused thereby.

In the manufacturing cost of these stoppers as heretofore made, which is about fifteen cents (15¢) per gross, the cork disk represents about two-thirds therof, so that by dispensing with an annular portion of the cork, which, in practice, is nearly an eighth of an inch wide, in the commercial stopper, I bring the cost of the cork down to less than eight cents (8¢) per gross and very materially cheapen the total cost of the stopper.

Having now described my invention, what I claim, is:

1. A bottle stopper comprising a cap having a depending flange adapted to pass over and engage the exterior of the neck of the bottle, and containing a packing disk of less diameter than the internal diameter of the cap but of greater diameter than the bore of the bottle, substantially as described.

2. A bottle stopper comprising a cap having a depending flange adapted to pass over and engage the exterior of the neck of the bottle, and containing a packing disk having a diameter substantially less than the external diameter of the mouth of the bottle and greater than the bore of the bottle.

3. A bottle stopper comprising a cap having a depending flange adapted to pass over and engage with the exterior of the neck of the bottle, and containing a packing disk concentrically arranged and secured therein, which disk is adapted to rest on the top of the inner portions or surface only, of the lip of the bottle when the cap is applied thereto.

4. A bottle stopper comprising a cap having a depending flange adapted to pass over and engage the exterior of the neck of the bottle, a packing disk located inside of the cap and of less diameter than the interior of the cap, the metal of the cap being set inward to grip and hold the packing disk in place.

In witness whereof, I subscribe my signature, in the presence of two witnesses.

GEORG KIRKEGAARD.
